UNITED STATES PATENT OFFICE.

ALBERT E. GRANT, OF NEW YORK, N. Y.

COMBINED BURNER AND GAS-GENERATOR UNIT.

1,393,358.

Specification of Letters Patent. Patented Oct. 11, 1921.

Application filed August 21, 1919, Serial No. 318,991. Renewed January 10, 1921. Serial No. 436,392.

To all whom it may concern:

Be it known that I, ALBERT E. GRANT, a subject of the King of Great Britain, residing at New York, in the county of New York and State of New York, have invented a new and useful Improvement in Combined Burner and Gas-Generator Units, of which the following is a full, clear, and exact description, reference being had to the accompanying drawings, forming part of this specification, in which—

Figure 1 is a side elevation of the preferred embodiment of the invention, the oil tank being shown in section;

Fig. 2 is a sectional view through the burner and gas generator, it also showing the water supply connections;

Fig. 3 is a bottom plan view of the gas-fixing chamber;

Fig. 4 is a plan view of the superheater coil;

Fig. 5 is a sectional view showing the automatic water shut-off valve;

Fig. 6 is a sectional view through one form of the steam and oil-mixing nozzles;

Fig. 7 illustrates a modification of the steam control;

Fig. 8 illustrates another modification of the steam control;

Fig. 9 illustrates still another modification of the steam control; and

Fig. 10 is a detail plan view along the line X—X of Fig. 2.

The present invention relates to a combined burner and gas generator unit, which is fed with water and oil. The water and oil are combined in the generator into a gas which is supplied to and burned at the burner. The heat from the burner serves to gasify the water and oil, and thereby maintain a continuous supply of gas to the burner. The burner and gas generator unit is particularly designed to be placed in the combustion chamber of steam boiler furnaces, hot water boiler furnaces, hot air furnaces, etc., but may be used any place where desired to generate heat.

The object of the invention is to provide an improved apparatus of this type, and particularly one which will automatically shut off the water and oil supply in case the flame for any reason is extinguished or goes out. The invention also relates to certain other arrangements and combinations of parts hereinafter more particularly pointed out, the advantages of which will be ap-

parent to those skilled in the art from the following description.

The illustrated embodiment of the invention may be briefly described as follows:

The burner proper 2 and the gas generator are mounted in and on a box 3, which is designed to be placed in the combustion chamber of the furnace to be heated. Water is supplied to a boiler 4 in which the water is converted into steam. The steam passes through a superheating coil 5, which is maintained at a high temperature, into an expansion chamber 6 in which the steam is still further heated and which serves as a steam reservoir to equalize the flow. The highly superheated steam passes from the expansion chamber 6 through a suitable regulating valve to a steam nozzle 7. The steam issuing from this nozzle draws vaporized oil through an oil nozzle 8. The steam and vaporized oil are mixed and pass into a fixing chamber 9, in which the water and oil and vapors are fixed into a permanent gas. This gas is supplied to and burned at the burner 2. The oil is supplied to the oil nozzle 8 from an oil tank 10, the oil being drawn by suction up through a vertical pipe 11, which passes through the burner box 3 and expansion chamber 6, so that the oil is preheated and vaporized.

The apparatus is described in detail as follows:

The water is taken from a water pipe 20, connected with the city water mains and passes through a reducing valve 21, in which the water pressure is reduced to the proper point. The reducing valve serves to maintain a reduced and constant pressure water feed for the burner. It is found that a pressure of about ten pounds to the square inch is satisfactory. The water after passing the reducing valve flows through pipe 22 and through check valve 23 into an equalizing reservoir 24. The top of the equalizing reservoir is closed so as to maintain an air cushion over the water therein. In case back pressures develop in the gas generator, it is taken care of by the equalizing reservoir. The water passing through the equalizing reservoir passes through the pipe 25 to the boiler 4. The pipe 25 is provided with a hand shut-off valve 26 and an automatic shut off valve 27. The valve 27 is shown in greater detail in Fig. 5. It comprises a conical valve 28, spring-pressed by a spring 29 against its seat and operated automatically

through an overflow receiving cup or vessel 30. The cup 30 is mounted on the valve stem rod 31 which, as shown in Fig. 2, is pivotally supported in a bearing 32. The cup 30 projects to one side of the rod 31, so that when the cup 30 is filled with water, the weight of the water will turn it down, thereby turning the valve stem rod 31, and closing the valve 27. The cup 30 is placed directly beneath the burner 2. In case the burner goes out, water will be supplied thereto until sufficient water drips from the burner through the hole 33 in the bottom of the box 3 into the cup 30, to fill the cup and shut off the automatic valve 27. The water from the pipe 25 passes into the boiler 4 which is heated by the burner 2. In the boiler 4, the water is converted into steam which passes from the top of the boiler 4 into the superheating coil 5. This coil 5 is illustrated in detail in Fig. 4. As shown in Figs. 1 and 2, the coil 5 is placed at the open top of the box 3 so as to receive the heat from the burner 2. In the superheating coil 5, the steam is superheated to a high temperature. It is found that in practice the coil is maintained at about a red heat. From the superheating coil 5, the steam passes into an equalizing or expansion chamber 6, which is a substantial duplicate in form of the boiler 4, being formed at the side of the box opposite the boiler 4. The expansion chamber 6 is exposed to direct heat from the burner 2, and serves to maintain and somewhat increase the temperature of the superheated steam. This equalizing or expansion chamber serves as a steam reservoir to insure a steadier flow of steam to the steam-discharge nozzle. The steam flows from the top of the expansion chamber 6, through a steam supply pipe 40, to a saturator indicated generally by the reference numeral 41. The saturator comprises the nozzle 7 through which the steam is discharged at high velocity, and a nozzle 8, through which the oil is sucked up by the high velocity steam.

As illustrated in Figs. 1 and 6, the height of the flame is controlled by means of a movable injector nozzle, which is threaded into the casing 42, and which may be adjusted to and from the oil supply nozzle 8, by means of a handle 43. By regulating the position of the adjustable steam nozzle, the suction on the oil may be varied, thereby raising and lowering the flame at the burner 2. The volume of steam generated may be controlled by regulating the water supply by means of the valves 21 and 26.

In Fig. 7 is illustrated a modification in which the flame is controlled by means of an adjustable reducing valve 44, which is inserted in the steam supply pipe between the expansion chamber and the steam injector nozzle 7. By adjusting the reducing

valve 44, the steam may be kept flowing with absolutely steady flow and pressure, so that the flame is maintained steady. A five-pound pressure at the reducing valve 44 is found, in practice, to give an absolutely steady low flame. As the reducing valve is opened up, the increased pressure enlarges the flame.

In Fig. 8 is illustrated a modification in which the flow of steam to the injector nozzle 7 is controlled by means of a hand valve 45, permitting the hand regulation, without, however, the automatic regulation of the reducing valve.

In Fig. 9 is illustrated still another modification in which the flow of steam to the injector nozzle 7 is controlled by means of a reducing valve 44 and a hand valve 45 giving both an automatic and a hand regulation.

The steam from the nozzle 7 creates suction from the mouth of the oil supply nozzle 8, drawing through it the previously vaporized oil. The steam and vaporized oil pass through a mixing nozzle 50, into a fixing chamber or coil 9. This fixing chamber is in the form of a tortuous coil formed on the bottom of the top plate 51, which is mounted on but spaced from the top of the box 3. The top plate 51 has openings 52, which allow the flame and the products of combustion to pass freely through this plate and around the fixing coil 9. The fixing chamber or coil 9 is maintained at almost a white heat. In it, the mixture of steam and oil vapor is subjected to a temperature which I estimate to be over 3700° F., and this causes the steam and oil vapor to combine as a fixed dry gas. Since the steam and oil are both preheated before entering the fixing chamber 9, it is possible to maintain this fixing chamber at a high heat. The gas from the fixing chamber 9 is led through pipe 55, to the burner 2, where it is consumed. It is found that the generator will produce more gas than is absolutely necessary to maintain sufficient heat at the burner to continuously gasify fresh supplies of water and oil. This permits some gas to be taken away from the burner, if desired, for storage or for use in other gas burners. For example, if the burner and generator unit is used in the fire box of a furnace for heating a house, gas may be drawn from it for use in a kitchen range or for illuminating purposes. As shown in Fig. 1, a branch pipe 56 is provided through which excess gas may be drawn away. If it is not desired to use such excess gas, all the gas may, of course, be consumed at the burner 2.

The burner 2, as illustrated, consists of a pipe having through it a number of holes 57, through which the gas issues. These holes are comparatively large, preferably about one-fourth of an inch in diameter.

It will be noted that there are no restricted openings in the gas-fixing chamber 9 or in the connections from the gas-fixing chamber to the burner. This prevents any stuffing 5 up of the burner or its connections. Moreover, there is no point at which carbonization can take place in the burner; but even if carbonization should take place, all of the holes are large enough so that it would 10 be difficult or impossible to stuff them up.

The oil is supplied from a larger oil receptacle, located at a safe distance, to a small oil tank 10, which holds about a gallon. The oil receptacle on the tank 10 is 15 maintained constant by means of a float valve 60. The oil flows through a connecting pipe 61, provided with a check valve 62, to the bottom of the oil pipe 11, which passes up through the burner box. As shown in the 20 drawings, this oil pipe 11 passes through the bottom of the burner box and then through the expansion chamber 6, where it is exposed to the highly superheated steam. The heat is generally found sufficient to vaporize 25 the oil, so that the oil in vapor, rather than liquid form, is drawn through the oil nozzle 8. The tank 10 is placed so that the normal oil flow will be at about the bottom or below the level of the burner. The oil 30 is drawn up to the saturator 41 by means of the suction injector action of the steam. If, for any reason, the burner is extinguished, or goes out, so that the generation of steam 35 is stopped, the supply of oil automatically ceases.

At the bottom of the burner box 3 is an asbestos pad 70, which acts as a wick to start the burner. To start the burner, oil is poured on the wick and burnt until the 40 temperature of the gas generator is brought to the proper starting point, after which the water and steam supply valves are adjusted so that the flame will be maintained at the desired point. The burner will then continue, the flame being automatically maintained at the point at which it was originally set.

In case any back pressure develops, due to sudden expansion of steam in the boiler, 50 the superheating coil or other parts of the gas generator, such expansion will back up the water through the pipe 25. The check valve 23 prevents the back pressure from backing up in the water main. The back 55 pressure is absorbed by the equalizing reservoir 24, into the bottom of which any steam through the pipe 25 is discharged and condensed by the water therein. The air cushion absorbs any shocks which may be 60 due to driving the water back through the pipe 25. During normal operation, however, the water flows continuously through the pipe 25 into the boiler 4, the equalizing reservoir 24 being provided as a safety device 65 to meet emergencies.

If, for any reason, the flame should be extinguished, the water is automatically shut off. Suppose that the flame of the burner 22 is accidentally extinguished. The water will continue to flow into the boiler 70 and will then fill up the superheating coil 5, the expansion chamber 6 and fixing chamber 9, and will flow down into the burner 2. The water will drop from the burner 2 into the cup 30, which when filled will move downwardly, turning the valve stem 31 and shutting off the water valve 27. The extinguishing of the burner 2 will, of course, immediately stop the production of steam, so that there will no longer be a suction drawing 75 the oil up through the nozzle 8, so that the oil will immediately fall in the pipe 11 to the level of the oil in the tank 10, thus precluding any danger from oil dripping from the burner.

The present invention relates to the same type of gas burner as I have disclosed in my copending application, Serial No. 279, 80 811, but discloses certain improvements therein.

While I have specifically illustrated and described the preferred embodiment of my invention, it will be understood that the invention is not limited to its illustrated embodiment, but may be embodied in other 85 structures within the scope of the following claims.

I claim:

1. A heating unit adapted to heat the fire chamber of a furnace or boiler, comprising 100 the combination of a flame forming burner, injector means in advance of said burner and adapted to mix oil and steam, an oil supply having a constant level below said injector means, a steam generator, independent of the furnace or boiler, heated by said burner flame and adapted to draw up automatically said oil to said injector, vaporize it and feed it to said burner, means for maintaining a substantially constant steam 105 flow from said generator to said injector while said burner is in operation, and means for stopping the flow of steam to the injector when the burner flame ceases.

2. A heating unit adapted to heat the fire 115 chamber of a furnace or boiler, comprising the combination of a flame forming burner, injector means in advance of said burner and adapted to mix oil and steam, an oil supply having a constant level below said 120 injector means, a steam generator, independent of the furnace or boiler, heated by said burner flame and adapted to draw up automatically said oil to said injector, vaporize it and feed it to said burner, and means 125 for maintaining a substantially constant steam flow from said generator to said injector while said burner is in operation, the said generator having a capacity approximately equal to supplying sufficient steam to 130

- draw up automatically said oil to said injector, vaporize it and feed it to the burner, whereby the steam generation and oil feed will cease contemporaneously with the cessation of burner flame.
3. A heating unit adapted to heat the fire chamber of a furnace or boiler, comprising the combination of a flame forming burner, injector means in advance of said burner and adapted to mix oil and steam, an oil supply having a constant level below said injector means, a steam generator, independent of the furnace or boiler, heated by said burner flame and adapted to draw up automatically said oil to said injector, vaporize it and feed it to said burner, means for maintaining a substantially constant steam flow from said generator to said injector while said burner is in operation, a fixing chamber heated by said burner intermediate the injector means and the burner, and means for stopping the flow of steam to the injector when the burner flame ceases.
4. In an oil burner adapted to be placed in the firebox of a furnace or boiler the combination with a water supply for the burner, of a generator unit therefor, an oil supply, means for automatically feeding the oil from said supply by the steam from said generator, and means for automatically shutting off the water supply by unconsumed liquid from said burner.
5. A combined gas burner and generator unit, comprising a burner, a fixing chamber for supplying gas to the burner, means for supplying steam to the fixing chamber including an inclosed steam nozzle through
- which the steam is discharged at high velocity, and means for supplying oil to the fixing chamber comprising an oil nozzle over which the high velocity steam is discharged, oil supply means having a constant level, and means adjustable from the outside for relatively adjusting the steam and oil nozzles to vary the suction exerted by the steam on the oil nozzle and regulate the proportions of steam and oil, substantially as described.
6. In an oil burner the combination with a base plate and overflow tray of a steam generator supported in spaced relation thereto comprising an integral casting having passages on opposite sides for generating steam, said passages being connected together and to a steam nozzle injector for supplying a mixture of steam and oil to the burner, and means for directing the burner flame between said passages.
7. In an oil burner the combination with a main water supply, of a generator adapted to be inserted in the firebox of a furnace or boiler, a combustible mixture forming nozzle supplied with steam from said generator, means for varying the supply of steam to said nozzle from said generator, and means for absorbing the back pressure of steam from said generator comprising a reservoir of water outside of said firebox and containing a body of water in said main water supply acting to condense any steam driven back by the pressure in said generator.
- In testimony whereof I have hereunto set my hand.

ALBERT E. GRANT.
